ORCHARD SPRAYING MACHINE

Richard H. Fish, Morgan Hill, Calif., assignor to
Air-O Fan Products Corporation, a corporation
of California

Application October 30, 1950, Serial No. 192,964

4 Claims. (Cl. 299—30)

1

This invention relates generally to improvements in orchard spraying machines used for the purpose of applying disease and pest control liquids to the orchard trees.

A major object of the present invention is to provide a compact, unitary, self-powered, centrifugal fan-type spray unit adapted to be arranged in novel combination with a high pressure hose and nozzle type spraying machine whereby to convert the same from a hand to an automatic sprayer. By automatic sprayer is meant a machine which travels between the orchard rows and discharges high velocity spray directly from a fan into the trees.

A further object of this invention is to provide a spray unit which is designed for ready and convenient mounting in place, whereby to facilitate the conversion of a hose and nozzle type spraying machine to an automatic type, as aforesaid.

Another object of the invention is to construct the spray unit so that it may function to emit a spray blast from one side or the other, or from both, selectively; the unit including novel adjustable air blast deflector vanes which control the pattern of the spray from each side of the machine.

An additional object of the invention is to provide a novel valve assembly, adjacent the tractor seat, for the selective control of the spray blasts to one side or the other, or both sides, as in the preceding paragraph.

It is also an object of the invention to provide a spray unit designed for ease and economy of manufacture.

Still another object of the invention is to provide a practical and reliable orchard spraying machine, and yet one which will be exceedingly effective for the purpose for which it is designed.

These objects are accomplished by means of such structure and relative arrangement of parts as will fully appear by a perusal of the following specification and claims.

In the drawings:

Fig. 1 is a side elevation of the orchard spraying machine.

Fig. 2 is a rear end elevation, partly broken away, of the unitary, self-powered spray unit employed in the machine.

Fig. 3 is a sectional elevation of said spray unit.

Fig. 4 is an enlarged fragmentary cross section of the valve assembly as mounted adjacent the operator's seat on the tractor.

Referring now more particularly to the characters of reference on the drawings, the numeral 1 indicates, generally, a tank trailer adapted to be coupled in driven relation by a tongue 2 to the rear of a tractor 3. The tank trailer 1 includes therein a tank 4 for liquid spray material, and a conduit 5 connects the tank 4 to a gas engine driven pump unit 6 likewise within the trailer 1.

2

A supply hose 7 leads out of the trailer 1 to supply the liquid spray under pressure from the pump unit 6.

In some adaptations a tank trailer as above may be used as a hose and nozzle type spraying machine, and in such event the supply hose 7 is extended, valve controlled, and fitted with a hand supported nozzle, by means of which an operator may manually direct said nozzle to spray orchard trees or the like.

The present invention contemplates the conversion of the above type of spraying machine to an automatic sprayer; i. e. a machine which sprays directly from a spray unit, fixed on the machine, into the adjacent orchard trees, such conversion being accomplished as follows:

At the rear end thereof the tank trailer 1 is formed with a rearwardly projecting platform 8, and a compact, unitary, self-powered centrifugal fan-type spray unit, indicated generally at 9, is mounted on such platform 8; such unit being constructed and functioning as follows:

The spray unit 9 comprises a base 10 secured to the platform 8, with an engine housing 11 upstanding from said base rearwardly of a centrifugal fan housing 12.

Within the housing 11 the base 10 supports a gas engine 13 which includes a starting crank 14 and an exhaust 15.

The engine 13 includes a direct-drive fan shaft 16 which extends rearwardly and coaxially into the centrifugal fan housing 12.

The centrifugal fan housing 12 includes a front plate 17, a back plate 18, and a bottom plate 19; said housing, above said bottom plate 19, being formed with an arcuate discharge slot 20 of at least 180° extent, disposed half on each side of the fan housing 12.

Radially inwardly of the discharge slot 20 there is a corresponding, outwardly tapering throat 21, which throat extends in matching relation about a centrifugal fan 22 mounted on the fan shaft 16; said throat running unbroken from opposite ends of the bottom plate 19.

The centrifugal fan 22 includes a hub 23, a front plate 24, and a back plate 25; there being a plurality of volute-like fan blades 26 extending toward the hub 23 between the plates 24 and 25 in equally circumferentially spaced, spider-like arrangement.

The back plate 18 of the fan housing and the back plate 25 of the centrifugal fan are formed with enlarged openings 27 and 28, respectively, for the purpose of air intake into the fan. The opening 27 has a grill-type guard 29 fitted thereover.

Radially out from the centrifugal fan 22, and within the tapering throat 21, there is a continuous row of radially arcuate deflector vanes 30; such vanes being spaced apart substantially equi-

distantly and being adjustably secured in said throat by studs 31 which project laterally outwardly from the lower end of each vane through the plates 17 and 18; said studs normally being maintained tight and against rotation by nuts 32. With this arrangement the deflector vanes 30 are normally held in fixed position but may be adjusted, preparatory to use of the machine, as working conditions may require.

The adjustable vanes 30 are concave on one side, which is for the purpose of redirecting the air flow from the fan to effectively control the spray pattern.

Substantially radially outwardly facing spray nozzles 33 extend in an arcuate path about the upper and side portions of the centrifugal fan 22, being disposed substantially in the slot 20 centrally between opposite sides thereof.

The nozzles 33 are in communication with, and are supported by, lateral fittings 34 which extend forwardly through the adjacent part of the fan housing, connecting—outwardly of the housing—with a corresponding manifold 35. There is a manifold 35 for each side of the spray unit 9; i. e. from a point adjacent the top downwardly to a point adjacent the corresponding end of the bottom plate 19. With this arrangement, the nozzles on one side of the machine are fed by one manifold, while the nozzles on the other side of the machine are fed by the other manifold.

Separate hoses 36 lead from a tractor mounted control valve assembly, indicated generally at 37, rearwardly along the tank trailer 1 to connection with the lower end of the corresponding manifold 35.

The control valve assembly 37 is preferably mounted alongside the operator's seat 38 on the tractor, being secured thereto by a clamp 39. The control valve assembly 37 comprises a T-fitting 40 connected, at the central leg, to the supply hose 7, and connected, at opposite ends, to the feed hoses 36, with manual valves 41 interposed between each such feed hose 36 and the corresponding end of said T-fitting 40.

In operation of the described orchard spraying machine, liquid spray material is fed under high pressure from the tank 4 through hose 7 to the control valve assembly 37.

By the selective manipulation of the valves 41 by the tractor operator, high pressure liquid spray can be fed through one or the other, or both simultaneously, of the feed hoses 36, to the end that spray emits from the nozzles 33 at either side, or both sides simultaneously, of the centrifugal fan 22.

With said centrifugal fan 22 driven at relatively high speed by the engine 13, a high velocity air blast delivers from the discharge slot 20, picking up the atomized liquid spray from the nozzles 33 and blowing it forcefully into the orchard trees along the row between which the machine is traveling.

By reason of the described selectively controlled valve assembly 37, the tractor operator, from the seat 38, may cause the machine to spray from either side, or both sides, as aforesaid, and as working conditions may require.

A combination orchard spraying machine as described provides for the practical, convenient, and effective spraying of orchard trees; the spray unit 9 being initially separate, unitary, and self-powered, which makes possible the ready conversion of a hose and nozzle type spraying machine into an automatic spraying machine, with the advantages attendant the latter.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. In combination, a tractor, a trailer coupled to the tractor, the trailer including means to supply a liquid spray under pressure, a platform at the rear of the trailer, a unitary self-powered spray unit mounted on the platform, a conduit system mainly exteriorly of the trailer connected between said spray supply means and the spray unit, and a control valve assembly in said conduit system mounted on the tractor adjacent and alongside the operator's station.

2. A combination, as in claim 1, in which the spray unit includes sets of spray nozzles adapted to discharge laterally outward from opposite sides of said unit; the conduit system having a separate conduit leading from the valve assembly on the tractor to each set of spray nozzles, and said assembly including a valve corresponding to each of said separate conduits.

3. In combination, a tractor, a trailer coupled to the tractor, the trailer including means to supply a liquid spray under pressure, a supply conduit leading forwardly from said means to the tractor, a valve assembly on the tractor adjacent the operator's station, the supply conduit connecting to the valve assembly, a feed conduit leading from the valve assembly rearwardly to adjacent the rear end of the trailer, the latter including a rear end platform, and a unitary self-powered spray unit mounted on the platform and connected with said feed conduit; the supply and feed conduits including flexible portions between the valve assembly and the trailer.

4. In combination with a wheel supported vehicle including means thereon to supply a liquid spray under pressure, a platform on the vehicle, a unitary self-powered spray unit mounted on the platform, and a valve controlled conduit system connected between said spray supply means and said spray unit; there being a tractor coupled to the vehicle, said system including a portion extending to adjacent the operator's station on the tractor, and a valve in said portion manually accessible to said operator and mounted on the tractor.

RICHARD H. FISH.
